HEM MEASURING STICK

Eva De Luca, 310 West End Ave.,
New York, N.Y. 10023

Filed Nov. 16, 1973, Ser. No. 416,609

Term of patent 14 years

Int. Cl. D10—04

U.S. Cl. D10—71

FIG. 1.

FIG. 2.

FIG. 3.

FIG. 4.

FIG. 5.

FIG. 6.

FIG. 1 is a front elevational view of a hem measuring stick showing my new design with an intermediate portion broken away for ease of illustration;

FIG. 2 is a rear elevational view thereof;

FIG. 3 is a side elevational view thereof;

FIG. 4 is a side elevational view of another embodiment of my new design of FIG. 1;

FIG. 5 is a front elevational view thereof; and

FIG. 6 is a rear elevational view thereof.

I claim:

The ornamental design for a hem measuring stick, substantially as shown and described.
